UNITED STATES PATENT OFFICE.

CHARLES BASHWINER, OF JAMAICA, NEW YORK, ASSIGNOR TO ACTIVE FOLDING BOX CO., INC., A CORPORATION OF NEW YORK.

FOLDABLE DISPLAY BOX.

Application filed October 23, 1920. Serial No. 418,942.

To all whom it may concern:

Be it known that I, CHARLES BASHWINER, a citizen of the United States, and a resident of Jamaica, borough of Queens, in the 5 county of Queens and State of New York, have invented certain new and useful Improvements in a Foldable Display Box, of which the following is a full, clear, and exact specification.

10 This invention relates to a class of containers composed of integral parts cut and scored from a single blank for being folded together when wanted for use.

My invention has for its object primarily 15 to provide a box or container designed to be employed for holding merchandise and various articles in a fashion to allow the box and its contents to be displayed for sale on an appropriate support, and which is of a 20 form adapted to be arranged on an incline so that the contents will be easily observable for attracting purchasers. The invention also contemplates the provision of the box by cutting and scoring it in entirety from 25 a single blank of card board or other suitable material in a manner to permit advertisements to be shown on the exterior parts of the box when folded by printing, embossing or otherwise inscribing if desired the 30 subject matter on only one surface of the blank, in order to lessen the cost of production, and furthermore the blank from which the box is folded is of a type permitting of a large saving in consumption of material by 35 reason of being adapted to be cut without practically any wastage.

A further object of the invention is to 40 provide a box combining simplicity of construction and unusual durability which may be made in any appropriate size, and which is of a form so that the requirement for glueing parts of the box are avoided.

With these and other objects in view, the 45 invention will be hereinafter more particularly described with reference to the accompanying drawings forming a part of this specification in which similar characters of reference indicate corresponding parts in all the views, and will then be pointed out in 50 the claims at the end of the description.

In the drawings, Fig. 1 is a plan of the 55 form of blank from which my improved box is folded.

Fig. 2 is an enlarged fragmentary per-

spective view showing parts of the box when 55 folded.

Fig. 3 is an enlarged fragmentary perspective view showing other parts of the box when folded.

Fig. 4 is an enlarged fragmentary perspective view showing still other parts of the box when folded, and

Fig. 5 is an enlarged perspective view showing the box when completely folded.

The box is provided by being folded from 60 a single blank, as 10, of card board or other appropriate flexible material, and the general form of this blank is substantially rectangular so that one or a number of the blanks may be cut or struck out of a single 65 sheet of the material which is usually made in rectangular or square sheets. The blank is cut and scored to form the assembled box with a bottom section A, a rear wall section 70 B, a front wall section C, two inner side 75 wall sections D, E and F, G, two outer side wall sections H and I, two side wall flaps J and K, a lid section L, two rear wall wing members M and N, two easel sections O and P, and two bracket wing members R and Q, 80 all of which may be made in suitable sizes according to the size of the box.

The bottom section A of the box is substantially rectangular, and this bottom section is provided by scoring the central parts 85 of blank, at 11 and 12, to provide side edges as well as being scored, at 13, to provide a rear edge and scored, at 14, to provide a front edge.

The rear wall section B extends from the 90 rear edge 13 of the bottom wall section A. This rear wall section is substantially rectangular and is formed by scoring the blank 10, at 15, 16, 17.

The front wall section C extends from the 95 front edge 14 of the bottom section A as well as being preferably of twice the width of the rear wall section B. The front wall section is provided by scoring the blank, at 18 and 19, and the blank is scored, at 20, 100 centrally lengthwise of the front wall section to provide two foldable parts 21 and 22 each of a size approximately similar to the size of the rear wall section B.

The member D of the inner side wall 105 section of the box extends from the end edge 15 of the rear wall section B, and the member E of this inner side wall section extends

from the edge 18 of the part 21 of the front wall section C. By scoring the blank 10, at 23, the member D of the inner side wall section is formed, and this member is approximately one-half the length of the edge 11 of the bottom section A. In the central part of the upper edge of the member D is a slot 24 which extends crosswise of the member to about one-half of its width, and 10 extending from the bottom of the slot across the member to its lower edge is a scoring 25 in the blank. The member E of this inner side wall section is of a length approximately similar to the width of the bottom 15 section A or approximately twice the length of the length of the member D, and in one edge of the member E is a slot 26 which is of a length similar to the length of the slot 24 of the member D. The member D is 20 foldable at the scoring 25 so that its slot 24 will be in the upper part of the folded edge, and the slot 26 of the member E is arranged so that by inserting the slotted part of the member E in the slotted edge 25 of the member D when folded both members will be releasably interlocked to provide the inner side wall section, as will be herein- 25 after more fully explained.

The member F of the second inner side 30 wall section extends from the end edge 16 of the rear wall section B, and the member G of this second inner side wall section extends from the edge 19 of the part 21 of the front wall section C. By scoring the blank, 35 at 27, the member F is formed, and this member is of a size similar to the member D of the other inner side wall section. In the central part of the upper edge of the member F is a slot 28 which extends cross- 40 wise of the member to about one-half its width, and extending from the bottom of the slot across the member to its lower edge is a scoring 29 in the blank. The member G of the second inner side wall section is of a size similar to the size of the member E 45 of the other inner side wall section, and in one edge of the member G is a slot 30 which is of a length similar to the length of the slot 28 of the member F. The member F 50 of the second inner side wall section is foldable at the scoring 27 so that the slot 28 will be in the upper part of its folded edge, and the slot 30 of the member G is arranged so that by inserting the slotted part of the 55 member G in the slotted edge of the member F when folded both members will be releasably interlocked to provide the inner side wall section, as will be more fully explained hereinafter.

60 The outer side wall section H extends from the edge 11 of the bottom section A of the blank, and this section is of a width substantially twice the widths of the inner side wall members D and E. The central 65 part of the outer side wall section H is

scored, at 31, from its upper to its lower edge to provide two foldable parts 32 and 33. The outer side wall section I extends from the edge 12 of the bottom section A of the blank, and this section is of a width approximately twice the width of the inner side wall members F and G. The central part of the outer side wall section I is scored, 70 at 34, from its upper edge to its lower edge to provide two foldable parts 35 and 36. 75

The side wall flap J extends from the edge 18 of the part 22 of the front wall section C, and this flap is of a size corresponding approximately to the size of one of the parts 32 and 33 of the foldable outer side wall section H. The side wall flap K extends from the edge 19 of the part 22 of the front wall section G, and this flap K is of a size substantially similar to the size of one of the parts 35 and 36 of the foldable outer side wall section I. 80

The lid section L of the box extends from the edge 17 of the rear wall section B, and this lid may be divided into two foldable parts, as 37 and 38, by scoring the blank 10 across the central part, as at 39. On the free end of the lid section may be a flap, as 40, which is provided by scoring the blank crosswise of the lid section, as at 41. The body proper of the lid including its 90 parts 37 and 38 are of a combined size similar to the size of the bottom section A, in order to permit the open top of the body to be opened and closed, while the flap 40 when folded at the scoring 41 may be inserted into the body of the box to lay 100 against the front wall section C when the lid is arranged in closed position on the open top of the box body.

The rear wall wing member M extends 105 from the lower edge of the member D of the inner side wall section upwardly alongside of the edge 23 of the member D. By scoring the blank, as at 42, the upper end of this wing member terminates on alignment with the scoring 39 of the lid section L, and the wing member M is foldable in halves by scoring the blank, as at 43, across the center of the member. The rear wall wing member N extends 110 from the lower edge of the member F upwardly alongside of the edge 27 of the member F. The blank 10 is scored, at 44, on alignment with the scoring 39 of the lid member L to provide the upper terminal of this wing member N, and this wing member N is also foldable in halves by scoring the blank, as at 45, crosswise of the wing member. 115

The easel section O is composed of a flap 46 and a foldable extension, as 47. The flap 46 extends upwardly from the upper edge 42 of the rear wall member M, and the extension 47 is disposed on an upward incline toward the flap 40 of the lid section L. The flap 46 is substantially rectangular, 120 125 130

while the extension preferably tapers upwardly toward its free end, and these two parts are relatively foldable by scoring the blank, as at 48, vertically on alignment with one of the side edges of the rear wall member M. The easel section P includes a flap 49 and a foldable extension 50. The flap 49 extends upwardly from the upper edge 44 of the rear wall member N, while the extension 50 is disposed on an upward incline toward the flap 40 of the lid section L. Both of these parts of the easel section P are of similar sizes and shapes to the sizes and shapes of the flap 46 and extension 47 of the easel section, and the parts are relatively foldable by scoring the blank, at 51, on vertical alignment with one of the side edges of the rear wall member N.

The bracket wing member R extends from a scoring, as 52, of the blank 10 which scoring provides one of the side edges of the part 37 of the lid section L, and this bracket member is approximately triangular in shape as well as projecting laterally from the lid section so that it may be foldably disposed rightangularly with respect to the lid section. The bracket wing member Q is also substantially triangular in shape of a size similar to the size of the bracket member R, and this bracket member Q extends from a scoring, as 53, of the blank 10 which provides the second side edge of the part 37 of the lid section L so that it is disposed laterally from the lid section in an opposite direction to the bracket member R for being foldable rightangularly relative to the lid section.

To assemble the parts of the box the blank 10 is folded at the scorings 11, 12, 13, 14 to form the bottom section A, and the blank is folded at the scorings 15, 16, 17 to provide the rear wall section B. By folding the blank at the scoring 18, 19, 20 the foldable front wall section C is formed, and with the folding of the blank at the scoring 17 the lid section L will be swung toward and above the bottom section A. With the folding of the blank at the scorings 15 and 16 the inner side wall members D and F will be turned upwardly, and with the upward folding of the rear wall section B the inner side wall members D and F are disposed edgewise on the bottom section A toward the front wall section C. With the folding of the blank at the scoring 14 the front wall section C will be turned upwardly from the bottom section A, and with the folding of the blank at the scorings 18 and 19 the inner side wall members E and G will be swung upwardly as well as being swung upon the bottom section A so that the slotted parts 26 and 30 of the members E and G may be inserted in the slotted edges 24 and 28 of the inner side wall members D and F following the creasing of the members D and F at their scorings 25 and 29. The members of the inner side walls of the box will then be releasably interlocked. With the folding of the scorings 11 and 12 of the bottom section A the outer side wall sections H and I will be turned upwardly from the bottom section so that the parts 32 and 35 of these outer wall sections will lay against the interlocked inner side wall members, and by folding the outer side wall members at their scorings 31 and 34 the parts 33 and 36 may be folded over the inner side wall members so that the parts 33 and 36 will lay against the interlocked inner side wall members interiorly of the box body. Also with the folding of the scorings 18, 19, 20 of the blank the flaps J and K and the part 22 of the front wall section will be turned upwardly from the bottom section for being disposed interiorly of the box body so that the part 22 of the front wall section will be disposed against the part 21 of the front wall section, while the flaps J and K will be disposed against the folded outer side wall sections H and I. A very strong and durable box body will thereby be provided. With the folding of the inner side wall members D and F the wing members M and N are turned rearwardly of the box body by the blank 10 being folded at the scorings 23 and 27. The wing members M and N are again folded at the scorings 43 and 45 of the blank so that both of the members will be disposed against the outer face of the rear wall section B. The easel sections O and P are then folded at the scorings 42 and 44 as well as being folded at the scorings 48 and 51 so that the flaps 46 and 49 will be disposed on the underside of the bottom section A under the rear wall section B so that the extensions 47 and 50 will be disposed also on the underside of the bottom section under the side walls of the body of the box to support the box on an incline. The lid section L may afterward be folded at the scoring 39 for disposing its part 38 on the part 37 with the flap disposed within the body of the box, and bracket wing members R and Q are turned rightangularly from the lid section for being disposed upon the upper edges of the side walls of the body of the box.

The wing members M and N are releasably fastened to the rear wall section B by providing in the folded edge or scoring 43 a slit 54 and by providing in the folded edge or scoring 45 a slit 55. In the rear wall section B at spaced parts of the scoring 17 are cut-out two locking elements 56 and 57 each of which is in the form of a dart or somewhat of a cone-shape.

When the wing members M and N are folded at the scorings 43 and 45 and disposed upon the exterior of the rear wall section the locking element 56 is inserted in the slit 54 of the member M, and the

locking element 57 is inserted in the slit 55 of the member N. In the scoring 13 of the bottom section A are two spaced slits 59 and 60. In the flap 46 of the easel section O at the scoring 42 is cut-out a locking element 61, while in the flap 49 of the easel section P at the scoring 44 is cut-out another locking element 62, and both of these locking elements are of a dart or cone-
10 shape. Following the insertion of the locking elements 56 and 57 in the slits 54 and 55, the locking elements 61 and 62 are inserted in the slits 59 and 60, and the wing members M and N will then be releasably
15 held to the rear wall section of the body of the box.

The easel sections O and P are releasably fastened to the body of the box after the sections are arranged under the bottom of
20 the body by providing in the scoring 11 of the bottom section A a slit 63, and in the scoring 12 of the bottom section is provided a slit 64. Protruding from the central part of one of the edges of the extension 47 of the easel section O is a locking element or tongue, as 65, and projecting from the central part of one of the edges of the extension 50 of the easel section P is another locking element or tongue, as 66.
25 When the extensions 47 and 50 are arranged on the underside of the bottom section A of the body of the box under its side walls, as above explained, the tongue 65 of the extension 47 is removably inserted in the
30 slit 63 of the scoring 11 of the bottom section, and the tongue 66 of the extension 50 is removably inserted in the slit 64 of the scoring 12 of the bottom section. The easel sections O and P will then be held for supporting the box on an incline.
35

The bracket wing members R and O are releasably attached to the body of the box for supporting the lid section L by providing in the scoring 31 of the outer side wall section H a slit 67 and in the scoring 34 of the second outer side wall section I is provided another slit 68. Protruding from the lower edge of the bracket member R is a locking element or tongue 69, and extending from the lower edge of the bracket member Q is a locking element or tongue 79. When the lid section L is arranged in an upstanding open position from the body of the box with the bracket members R and Q disposed on the creased scorings of the outer side wall sections H and I the tongue 69 of the bracket member R is removably inserted in the slit 67 of the outer side wall section H and the tongue 70 of the bracket member Q is removably inserted in the slit 68 of the outer side wall section I. The lid section L will then be retained in open position above the body of the box whether the parts of the lid section are folded or unfolded. A foldable
60
65

display box of a simple and very durable construction is thus provided for allowing articles to be attractively displayed for sale, and by providing the lid section L in its foldable parts 37 and 38 so that the part 70 38 may be disposed on the part 37 advertising matter may be provided to appear on the exterior of the box by printing or otherwise inscribing one surface of the blank 10; in order to avoid inscribing both 75 surfaces of the blank.

In the foregoing description, I have embodied the preferred form of my invention, but I do not wish to be understood as limiting myself thereto as I am aware that 80 modifications may be made therein without departing from the principle or sacrificing any of the advantages of this invention, therefore I reserve to myself the right to make such changes as fairly fall within the 85 scope thereof.

Having thus described my invention, I claim as new and desire to secure by Letters Patent:—

1. A foldable display box, comprising a 90 body having an open top with a bottom section, a rear wall section foldable upwardly from the bottom section, a front wall section divided into two parts also foldable upwardly from the bottom, interlocking inner side wall members foldable from the rear wall section and from the front wall section, side wall outer sections on the ends of the bottom section, foldable over the inner side wall sections when their members are interlocked, side wall inner flaps extending from the ends of the second part of the front wall section, foldable and insertable in the body to lay against the outer side wall sections, and rear wing 95 members on the interlocking inner side wall members of the rear wall section, foldable upon the outer face of the rear wall section, all of said parts being cut and foldably scored from a single blank whereby advertising matter provided on one face of the blank may be arranged to appear on the exterior faces of the parts of the box.
100

2. A foldable display box, comprising a body having an open top with a bottom section, a rear wall section foldable upwardly from the bottom section, a front wall section also foldable upwardly from the bottom, interlocking inner side wall members, foldable from the ends of the rear wall section and from the ends of the front wall section, side wall outer sections on the ends of the bottom section, foldable over the inner side wall sections when their members are interlocked, rear wing members on the interlocking inner side wall members of the rear wall section foldable upon the outer face of the rear wall section, and two easel sections, one on each of the rear wing members, both of the easel sections being foldable
110
120
125
130

under the rear part of the bottom of the box to support the body on an incline, all of said parts being cut and foldably scored from a single blank whereby advertising matter provided on one face of the blank may be arranged to appear on the exterior faces of the parts of the box.

3. A foldable display box, comprising a body having an open top with a bottom section, a rear wall section foldable upwardly from the bottom section, a front wall section also foldable upwardly from the bottom, interlocking inner side wall members, foldable from the ends of the rear wall section and from the ends of the front wall section, side wall outer sections on the ends of the bottom section, foldable over the inner side wall sections when their members are interlocked, rear wing members on the interlocking inner side wall members of the rear wall section, foldable upon the outer faces of the rear wall section, two easel sections, one on each of the rear wing members, both of the easel sections being foldable under the rear part of the bottom of the box to support the body on an incline, a lid section on the rear wall section for opening and closing the top of the body and the lid being divided crosswise into two parts for being folded toward the open top of the body, two bracket wings, one on each end of one of the parts of the lid section for being foldably disposed upon the upper edge of a side wall of the body, locking elements for releasably fastening the bracket wings of the lid to the side walls, locking means for releasably fastening the rear wall members to the rear wall section of the body, and means for releasably fastening the easel sections to the bottom section of the body, all of said parts being cut and foldably scored from a single blank whereby advertising matter provided on one face of the blank may be arranged to appear on the exterior faces of the parts of the box.

4. A foldable display box, comprising a body having an open top with a bottom section, a rear wall section foldable upwardly from the bottom section, a front wall section also foldable upwardly from the bottom, interlocking inner side wall members, foldable from the ends of the rear wall section and from the ends of the front wall section, side wall outer sections on the ends of the bottom section, foldable over the inner side wall sections when their members are interlocked, rear wing members on the interlocking inner side wall members of the rear wall section, foldable upon the outer faces of the rear wall section, two easel sections, one on each of the rear wing members, both of the easel sections being foldable under the rear part of the bottom of the box to support the body on an incline, a lid section on the rear wall section for opening and closing the top of the body and the lid being divided crosswise into two parts for being folded toward the open top of the body, two bracket wings, one on each end of one of the parts of the lid section for being foldably disposed upon the upper edge of a side wall of the body, locking elements for releasably fastening the bracket wings of the lid to the side walls, locking means for releasably fastening the rear wall members to the rear wall section of the body, and means for releasably fastening the easel sections to the bottom section of the body, all of said parts being cut and foldably scored from a single blank whereby advertising matter provided on one face of the blank may be arranged to appear on the exterior faces of the parts of the box.

This specification signed and witnessed this 22 day of October A. D. 1920.

CHARLES BASHWINER.

Witness:

J. FREDERICK CRYER.
